**UNDERGROUND STORAGE TANK FILLER NECK
AND CLOSURE CAP CONSTRUCTION****Frank H. Mellberg, Chicago, Ill., assignor of one-half to
Harry A. Mellberg, Rockford, Ill.****Filed Sept. 22, 1954, Ser. No. 457,663****9 Claims. (Cl. 220—40)**

This invention relates to filler caps, and, more particularly, relatively large diameter caps such as are required for underground storage tanks containing gasoline, kerosene, fuel oil, and the like.

The caps now being used on such tanks are objectionable because of the great difficulty in removing the same in cold weather when freezing conditions make turning of the caps practically impossible, a further objection being that when a cap was removed there was nothing to tie it up with respect to any one tank out of a group and nothing marked on it to identify the contents of the tank, with the result that many costly mistakes were made in the ensuing confusion. It is, therefore, the principal object of my invention to provide a cap of improved design and construction that avoids the objections mentioned, the same, to be more specific, including the following improvements:

(1) there is provided a downwardly tapered reduced rim portion on the cap which is received in a correspondingly tapered counterbore provided in the upper end portion of the neck to which the cap is applied, thereby making for easier release of the cap in the event it is frozen tight;

(2) there are three spring tongues secured to the underside of the cap in equally circumferentially spaced relation as retaining means engageable under inward projections provided therefor in equally circumferentially spaced relation in the neck and these tongues have angularly inclined laterally extending portions adapted to act as sled runners to ride up on inclined surfaces provided on top of the aforesaid projections whereby to help lift the cap in the rotation thereof in the opening direction, the other side of each of said tongues also having angularly inclined lateral extensions for a similar sled runner effect in riding under said projections when the cap is turned in the opposite direction in closing, whereby to spring said tongues downwardly and cause the cap to be tightly resiliently engaged with a compressible gasket as it is moved home;

(3) said tongues are inclined in a radial direction as are also the undersides of the projections to help center the cap with respect to the neck as the tongues ride under the projections in the turning of the cap in the closing direction;

(4) there are vertical stop shoulders provided on the bottoms of the projections in the neck against which the tongues engage to limit turning of the cap in closing, thereby indicating to the operator when the cap reaches the fully closed position, and

(5) said cap is provided with an overhanging flange for protection of the neck against ingress of moisture, snow or dirt, and this flange is provided also with circumferentially spaced peripheral notches which, being at the maximum radius, insures easiest turning of the cap by any means entered therein.

2

The invention is illustrated in the accompanying drawings, wherein—

Fig. 1 is a top view of the cap of my invention; Fig. 2 is a top view of the neck with the cap applied and indicated as being in fully closed position on the cap's three spring tongues being shown and their fastening screws being indicated in section on the line 2—2 of Fig. 4;

Fig. 3 is a developed view on line 3—3 of Fig. 2, showing one of the cap's spring tongues in a position corresponding to the start of the drawing down of the cap in the fastening thereof, if the cap is considered as about to be turned in a clockwise direction, or the position in which the cap is about to be cammed upwardly in the removal thereof by the three spring tongues riding up on the three inclined cam surfaces provided for that purpose in the neck, an intermediate portion of the view being broken away, as indicated, in order to save space and permit showing the parts on a larger scale, and

Fig. 4 is a view partly in side elevation and partly in vertical section on line 4—4 of Fig. 2 but indicating the cap in the same position as in Fig. 3, and showing the wrench of my invention applied to the cap for turning the same.

The same reference numerals are applied to corresponding parts throughout these views.

Referring to the drawings, it will be understood that the neck indicated at 5 has its upper end disposed at or slightly above ground level, and has a filler pipe 6 threaded into its lower end 7 and extending down to and connected with an underground tank (not shown). The neck 5 contains some of the improvements of my invention, the rest being embodied in the cap 8 and wrench 9. A flexible chain is diagrammatically indicated at 10 as provided between an eye 11 provided on the bottom of the cap 8 and a suitable anchor 12 provided inside the neck 5, whereby to make certain that the right cap is always returned to the associated neck and thereby insure correct identification of the tank's contents, especially if the caps are painted different colors according to a code to identify the different liquids stored, or, better still, if they are labelled on top, as shown at 13, for example, to positively identify the given commodity. The tieup of caps to necks, plus the identifying markings, are obviously enough to eliminate any further likelihood of confusion and the costly mistakes made heretofore are not apt to occur again.

The cap 8 comprises a cast circular body 14 having a downwardly projecting annular rim 15 concentric therewith, and a radially outwardly projecting marginal flange 16, in the periphery of which are provided, preferably at 90° intervals, diametrically opposed notches 17 for cooperation with the drive teeth or lugs 18 of the wrench 9, as shown in Fig. 4. The outer periphery 19 of rim 15 tapers downwardly and there is a matching taper in the counterbore 20 in the upper end of the neck 5 in which the rim 15 fits fairly freely for centering of the cap, the compression by the rim of a slightly compressible leather gasket ring 21 being relied upon for a good seal when the cap is applied and turned all the way home. There is then still a small clearance of a few thousandths of an inch between the periphery 19 of the rim 15 and the counterbore 20 as distinguished from a wedging fit, the purpose being to insure freedom of turning in the loosening of the cap, the few thousandths of an inch clearance being insufficient to give rise to any likelihood of moisture entering and freezing and thus preventing turning of the cap when it is to be removed. The ring 21 is set into an annular retaining groove 22

provided at the bottom 23 of the counterbore 20. The flange 16 overhangs the outside of neck 5 sufficiently to shield it against ingress of any water, snow or dirt, and the notches 17 are purposely made shallow enough radially of the flange to leave a little overhang at those points for further shielding of the joint between the cap and neck.

There are three radially disposed, equally circumferentially spaced spring tongues 24 of elongated form that are secured at their inner ends by screws 25 to the bottom of a central boss 26 on cap 8. These tongues project downwardly at an acute angle from the horizontal plane of the bottom of boss 26 and their T-shaped outer end portions 27 are arranged in the application of the cap to drop down in the three entrance spaces 28 left for them between three radially inwardly extending projections 29 cast integral with the inside of neck 5 just below the bottom 23 of counterbore 20. The projections 29 each provide an elongated bottom cam surface 30 extending circumferentially of one end portion thereof from the entrance 28 at one end thereof and terminating at a vertical stop shoulder 31 intermediate the ends thereof, and an elongated top cam surface 32 extending circumferentially of the other end portion thereof from the entrance 28 at that end thereof. Surfaces 30 and 32, it will be understood are inclined both circumferentially, as appears in Fig. 3, and radially like tongues 24, as appears in Figs. 3 and 4. The tongues 24 have the arms of the T-shaped outer end portions 27 bent downwardly, as best appears in Fig. 3, to provide inclined sled runners 33 and 34 for slidable engagement on the cam surfaces 30 and 32, respectively, the engagement of runners 33 on surfaces 30 causing downward deflection or springing of the tongues 24 so as to permit the tongues to engage under the surfaces 20 and hold the cap 8 closed tightly under spring pressure, whereas engagement of the runners 34 on surfaces 32, when the cap 8 is turned in the opposite direction, as in opening, causes upward springing of the tongues to apply a good lift on the cap 8 to help unseat it and raise it so that it can be easily removed. The radial inclination of the tongues 24 and the corresponding radial inclination of the cam surfaces 30 helps to center the cap with respect to the neck the instant the sled runners 33 on the tongues 24 engage the surfaces 30 in the turning of the cap in the closing direction, the downward pull on the cap exerted by the tongues 24 being, therefore, substantially equalized, so that the cap can be turned home much more easily than would otherwise be true. The downward inclination of surfaces 30 is shown in Fig. 3 as being rather slight but this inclination can, of course, be increased if it is desired to have the cap held down with increased spring pressure by increased deflection of the spring tongues 24, or the surface 30 may be horizontal, if no increase in hold-down pressure is desired. When the sled runners 33 strike the stop shoulders 31, the operator knows that the cap is fully closed. When the cap is turned in the opposite direction for removal the operator is immediately aware by "feel" when the tongues 24 ride off surfaces 30 and onto surfaces 32. The cap is loose when the tongues 24 reach spaces 28 and it is lifted off its seat as the tongues ride up on surfaces 32.

In conclusion, attention is called to Fig. 4 showing the spanner wrench 9. The body thereof is of elongated form, appreciably longer than the diameter of the cap 8, and is designed to extend diametrically across the top of the cap in the manner shown. It has two lugs or teeth 18 on diametrically opposite ends of its downwardly offset middle portion 35, which fit in the notches 17 on the cap to connect the wrench to the cap for drive purposes. The upwardly bent end portions 36 both terminate in handles 37 and these, of course, may be of any desired length so as to provide the desired amount of leverage in tightening and loosening the cap. While the lugs 18 are herein shown as fastened to the body of the wrench by means of rivets 38, it will, of course, be understood that they may

be welded in place or formed integral with the body of the wrench.

It is believed the foregoing description conveys a good understanding of the objects and advantages of my invention. The appended claims have been drawn to cover all legitimate modifications and adaptations.

I claim:

1. In a filler neck and closure cap combination comprising a filler neck having a bore and a counterbore provided therein with an annular shoulder defined therebetween, a cap for said neck having a downwardly projecting annular rim portion entered in said counterbore, and a gasket ring arranged to be compressed between the aforesaid annular shoulder and the downwardly projecting rim portion of said cap to effect a seal, improved means for detachably securing said cap in place compressing said gasket ring, comprising a plurality of circumferentially elongated projections in said bore in circumferentially spaced relation below said annular shoulder extending radially inwardly, each projection having cam surfaces extending circumferentially inwardly from the top and bottom of the opposite ends, respectively, the bottom cam surface on each projection being adjacent to the top cam surface of the next projection, and a plurality of elongated spring tongues mounted on the bottom of said cap extending radially outwardly from the center thereof and arranged so that the outer end portions thereof are movable downwardly in the spaces between said projections and are disposed approximately in the horizontal plane of the ends of the bottom cam surfaces when the cap is seated, said tongues being sprung downwardly when slidably engaged with the bottom cam surfaces in the rotation of the cap in a closing direction, whereby to effect compression of the gasket ring, and said tongues being sprung upwardly when slidably engaged on the top cam surfaces when the cap is turned in the opposite direction, whereby to unseat the cap, the outer end portions of said spring tongues being T-shaped providing laterally projecting arms on opposite sides thereof, said arms being inclined downwardly, one to reach under the bottom cam surfaces associated therewith and the other to ride on top of the top cam surfaces associated therewith.
2. In a filler neck and closure cap combination comprising a filler neck having a bore and a counterbore provided therein with an annular shoulder defined therebetween, a cap for said neck having a downwardly projecting annular rim portion entered in said counterbore, and a gasket ring arranged to be compressed between the aforesaid annular shoulder and the downwardly projecting rim portion of said cap to effect a seal, improved means for detachably securing said cap in place compressing said gasket ring, comprising a plurality of circumferentially elongated projections in said bore in circumferentially spaced relation below said annular shoulder extending radially inwardly, each projection having cam surfaces extending circumferentially inwardly from the top and bottom of the opposite ends, respectively, the bottom cam surface on each projection being adjacent the top cam surface of the next projection, and a plurality of elongated spring tongues mounted on the bottom of said cap extending radially outwardly from the center thereof and arranged so that the outer end portions thereof are movable downwardly in the spaces between said projections and are disposed approximately in the horizontal plane of the ends of the bottom cam surfaces when the cap is seated, said tongues being sprung downwardly when slidably engaged with the bottom cam surfaces in the rotation of the cap in a closing direction, whereby to effect compression of the gasket ring, and said tongues being sprung upwardly when slidably engaged on the top cam surfaces when the cap is turned in the opposite direction, whereby to unseat the cap, the outer end portions of said spring tongues being T-shaped providing laterally projecting arms on opposite sides thereof, said arms being inclined downwardly, one to reach under the bottom cam surfaces associated therewith and the other to ride on top of the top cam surfaces associated therewith.

sides thereof, said arms being inclined downwardly, one to reach under the bottom cam surfaces associated therewith and the other to ride on top of the top cam surfaces associated therewith, the latter arm having a reverse bend on the outer end portion thereof forming a sled runner having a portion thereof at the approximate inclination of the top cam surfaces.

3. In a filler neck and closure cap combination comprising a filler neck having a bore and a counterbore provided therein, and a cap for said neck having a downwardly projecting annular rim portion entered in said counterbore, improved means for detachably securing said cap in place comprising a plurality of circumferentially elongated projections in said bore in circumferentially spaced relation extending radially inwardly, each projection having cam surfaces extending circumferentially inwardly from the top and bottom of the opposite ends, respectively, the bottom cam surface on each projection being adjacent the top cam surface of the next projection, and a plurality of elongated spring tongues mounted on the bottom of said cap extending radially outwardly from the center thereof and arranged so that the outer end portions thereof are movable downwardly in the spaces between said projections and are disposed approximately in the horizontal plane of the ends of the bottom cam surfaces when the cap is seated, said tongues being sprung downwardly when slidably engaged with the bottom cam surfaces in the rotation of the cap in a closing direction, whereby to cause tighter seating of the cap, and said tongues being sprung upwardly when slidably engaged on the top cam surfaces when the cap is turned in the opposite direction, whereby to unseat the cap, the outer end portions of said spring tongues being T-shaped providing laterally projecting arms on opposite sides thereof, said arms being inclined downwardly, one to reach under the bottom cam surfaces associated therewith and the other to ride on top of the top cam surfaces associated therewith.

4. In a filler neck and closure cap combination comprising a filler neck having a bore and a counterbore provided therein, and a cap for said neck having a downwardly projecting annular rim portion entered in said counterbore, improved means for detachably securing said cap in place comprising a plurality of circumferentially elongated projections in said bore in circumferentially spaced relation extending radially inwardly, each projection having cam surfaces extending circumferentially inwardly from the top and bottom of the opposite ends, respectively, the bottom cam surface on each projection being adjacent the top cam surface of the next projection, and a plurality of elongated spring tongues mounted on the bottom of said cap extending radially outwardly from the center thereof and arranged so that the outer end portions thereof are movable downwardly in the spaces between said projections and are disposed approximately in the horizontal plane of the ends of the bottom cam surfaces when the cap is seated, said tongues being sprung downwardly when slidably engaged with the bottom cam surfaces in the rotation of the cap in a closing direction, whereby to cause tighter seating of the cap, and said tongues being sprung upwardly when slidably engaged on the top cam surfaces when the cap is turned in the opposite direction, whereby to unseat the cap, the outer end portions of said spring tongues being T-shaped providing laterally projecting arms on opposite sides thereof, said arms being inclined downwardly, one to reach under the bottom cam surfaces associated therewith and the other to ride on top of the top cam surfaces associated therewith, the latter arm having a reverse bend on the outer end portion thereof forming a sled runner having a portion thereof at the approximate inclination of the top cam surfaces.

5. In a filler neck and closure cap combination, comprising a filler neck having a bore and a counterbore provided therein, and a cap for said neck having a downward-

ly projecting annular rim portion entered in said counterbore, improved means for detachably securing said cap in place comprising three evenly circumferentially spaced circumferentially elongated projections in said bore extending radially inwardly, each projection having cam surfaces extending circumferentially inwardly from the top and bottom of the opposite ends, respectively, the bottom cam surface on each projection being adjacent the top cam surface of the next projection, and three evenly circumferentially spaced elongated spring tongues mounted on the bottom of said cap extending radially outwardly from the center thereof and arranged so that the outer end portions thereof are movable downwardly in the spaces between said projections and are disposed approximately in the horizontal plane of the ends of the bottom cam surfaces when the cap is seated, said tongues being sprung downwardly when slidably engaged with the bottom cam surfaces in the rotation of the cap in a closing direction, whereby to cause tighter seating of the cap substantially uniformly circumferentially thereof, and said tongues being sprung upwardly when slidably engaged on the top cam surfaces when the cap is turned in the opposite direction, whereby to unseat the cap with substantially uniform lift circumferentially thereof, the outer end portions of said spring tongues being T-shaped providing laterally projecting arms on opposite sides thereof, said arms being inclined downwardly, one to reach under the bottom cam surfaces associated therewith and the other to ride on top of the top cam surfaces associated therewith.

6. In a filler neck and closure cap combination, comprising a filler neck having a bore and a counterbore provided therein, and a cap for said neck having a downwardly projecting annular rim portion entered in said counterbore, improved means for detachably securing said cap in place comprising three evenly circumferentially spaced circumferentially elongated projections in said bore extending radially inwardly, each projection having cam surfaces extending circumferentially inwardly from the top and bottom of the opposite ends, respectively, the bottom cam surface on each projection being adjacent the top cam surface of the next projection, and three evenly circumferentially spaced elongated spring tongues mounted on the bottom of said cap extending radially outwardly from the center thereof and arranged so that the outer end portions thereof are movable downwardly in the spaces between said projections and are disposed approximately in the horizontal plane of the ends of the bottom cam surfaces when the cap is seated, said tongues being sprung downwardly when slidably engaged with the bottom cam surfaces in the rotation of the cap in a closing direction, whereby to cause tighter seating of the cap substantially uniformly circumferentially thereof, and said tongues being sprung upwardly when slidably engaged on the top cam surfaces when the cap is turned in the opposite direction, whereby to unseat the cap with substantially uniform lift circumferentially thereof, the outer end portions of said spring tongues being T-shaped providing laterally projecting arms on opposite sides thereof, said arms being inclined downwardly, one to reach under the bottom cam surfaces associated therewith and the other to ride on top of the top cam surfaces associated therewith, the latter arm having a reverse bend on the outer end portion thereof forming a sled runner having a portion thereof at the approximate inclination of the top cam surfaces.

7. In a filler neck and closure cap combination comprising a filler neck having a bore and a counterbore provided therein with an annular shoulder defined therebetween, a cap for said neck having a downwardly projecting annular rim portion entered in said counterbore, and a gasket ring arranged to be compressed between the aforesaid annular shoulder and the downwardly projecting rim portion of said cap to effect a seal, improved means for detachably securing said cap in place compressing said gasket ring, comprising a plurality of circumfer-

entially elongated projections in said bore in circumferentially spaced relation below said annular shoulder extending radially inwardly, each projection having cam surfaces extending circumferentially inwardly from the top and bottom of the opposite ends, respectively, the bottom cam surface on each projection being adjacent the top cam surface of the next projection, and a plurality of elongated spring tongues mounted on the bottom of said cap extending radially outwardly from the center thereof and arranged so that the outer end portions thereof are movable downwardly in the spaces between said projections and are disposed approximately in the horizontal plane of the ends of the bottom cam surfaces when the cap is seated, said tongues being sprung downwardly when slidably engaged with the bottom cam surfaces in the rotation of the cap in a closing direction, whereby to effect compression of the gasket ring, and said tongues being sprung upwardly when slidably engaged on the top cam surfaces when the cap is turned in the opposite direction, whereby to unseat the cap, the outer end portions of said spring tongues being T-shaped providing laterally projecting arms on opposite sides thereof, one of which arms has a downwardly and outwardly inclined top surface for slidable engagement with the bottom cam surface associated therewith, and the other of which arms has an upwardly and outwardly inclined bottom surface for slidable engagement with the top cam surface associated therewith.

8. In a filler neck and closure cap combination comprising a filler neck having a bore and a counterbore provided therein, and a cap for said neck having a downwardly projecting annular rim portion entered in said counterbore, improved means for detachably securing said cap in place comprising a plurality of circumferentially elongated projections in said bore in circumferentially spaced relation extending radially inwardly, each projection having cam surfaces extending circumferentially inwardly from the top and bottom of the opposite ends, respectively, the bottom cam surface on each projection being adjacent the top cam surface of the next projection, and a plurality of elongated spring tongues mounted on the bottom of said cap extending radially outwardly from the center thereof and arranged so that the outer end portions thereof are movable downwardly in the spaces between said projections and are disposed approximately in the horizontal plane of the ends of the bottom cam surfaces when the cap is seated, said tongues being sprung downwardly when slidably engaged with the bottom cam surfaces in the rotation of the cap in a closing direction, whereby to cause tighter seating of the cap, and said tongues being sprung upwardly when slidably engaged on the top cam surfaces when the cap is turned in the opposite direction, whereby to unseat the cap, the outer end portions of said spring tongues being T-shaped providing laterally projecting arms on opposite sides there-

of, one of which arms has a downwardly and outwardly inclined top surface for slidable engagement with the bottom cam surface associated therewith, and the other of which arms has an upwardly and outwardly inclined bottom surface for slidable engagement with the top cam surface associated therewith.

9. In a filler neck and closure cap combination, comprising a filler neck having a bore and a counterbore provided therein, and a cap for said neck having a downwardly projecting annular rim portion entered in said counterbore, improved means for detachably securing said cap in place comprising three evenly circumferentially spaced circumferentially elongated projections in said bore extending radially inwardly, each projection having cam surfaces extending circumferentially inwardly from the top and bottom of the opposite ends, respectively, the bottom cam surface on each projection being adjacent the top cam surface of the next projection, and three evenly circumferentially spaced elongated spring tongues mounted on the bottom of said cap extending radially outwardly from the center thereof and arranged so that the outer end portions thereof are movable downwardly in the spaces between said projections and are disposed approximately in the horizontal plane of the ends of the bottom cam surfaces when the cap is seated, said tongues being sprung downwardly when slidably engaged with the bottom cam surfaces in the rotation of the cap in a closing direction, whereby to cause tighter seating of the cap substantially uniformly circumferentially thereof, and said tongues being sprung upwardly when slidably engaged on the top cam surfaces when the cap is turned in the opposite direction, whereby to unseat the cap with substantially uniform lift circumferentially thereof, the outer end portions of said spring tongues being T-shaped providing laterally projecting arms on opposite sides thereof, one of which arms has a downwardly and outwardly inclined top surface for slidable engagement with the bottom cam surface associated therewith, and the other of which arms has an upwardly and outwardly inclined bottom surface for slidable engagement with the top cam surface associated therewith.
